COMBINATION BACK REST AND BAG
STRUCTURE

Robert N. Leeman, Malden, Mass.

Application September 4, 1946, Serial No. 694,721

2 Claims. (Cl. 155—153)

1

This invention relates to a combination back rest and bag structure.

The object of the invention is to provide a novel apparatus which may be used with advantage as an efficient back rest adapted to be erected upon the beach, lawn, or other surface, and when folded up to form a bag in which various articles such as bathing suits, lunch, and the like, may be conveniently carried during the transportation of the back rest.

With this general object in view, and such others as may hereinafter appear, the invention consists in the combination back rest and bag structure hereinafter described and particularly defined in the claims at the end of this specification.

In the drawings, Fig. 1 is a side elevation of the apparatus in its erected position; Fig. 2 is a plan of the inner side of the apparatus with the back rest folded preparatory to the formation of the bag; Fig. 3 is a similar view of a modification of the structure shown in Fig. 2 to be referred to; Fig. 4 is a sectional detail taken on the line 4—4 of Fig. 2; Fig. 5 is a side elevation of the bag structure formed by folding up the combination back rest and bag structure shown in Fig. 1; Fig. 6 is an end elevation of the structure shown in Fig. 5; and Fig. 7 is an end elevation of the modified form of structure shown in Fig. 3, folded into bag forming position.

In general, the present invention contemplates a back rest adapted to be erected upon the beach, or the like, comprising an open framework provided with a strut member hinged to the upper portion of the open framework and the straps or equivalent means for limiting the outward movement of the strut so as to permit the framework to be maintained in an upright but inclined position upon the beach. The face of the framework is covered by a sheet of flexible material such as canvas, webbing, or the like, for the entire length thereof, and the sheet is extended beyond the bottom of the framework for a length at least equal to the length of the back rest forming portion of the sheet, thus forming a skirt on which a person may sit when using the apparatus as a back rest. When it is desired to utilize the apparatus as a bag, and also during transportation of the apparatus to and from the beach, the hinged supporting strut member may be swung inwardly in a substantially parallel relation to the main supporting member of the back rest, and the extended skirt portion of the flexible sheet folded under the lower end of the back rest and upwardly into substantially parallel relation to the back

2

rest forming portion of the sheet whereby to form a bag structure within which various articles such as bathing suits, and the like, may be carried. In one form of the invention flexible side members are provided, arranged to form ends for the bag, and in another form of the invention a supplemental framework is provided secured to the skirt portion of the sheet to cooperate with the main supporting framework of the back rest to form the ends of the bag structure.

Referring now to the drawings the present back rest and bag structure comprises in general an open framework 10 substantially U-shaped and a strut 12 hinged to the upper end of the U-shaped frame for supporting the same in an inclined upright position, as shown in Fig. 1. An elongated sheet 14 of flexible material such as canvas, rubber, plastic, cloth or the like is secured to the open frame to form the back rest surface 16, and the elongated sheet 14 extends beyond the frame a distance substantially equal to the length attached to the frame to form a skirt portion 18 on which a person may sit while using the back rest. As thus constructed the lower half or skirt portion 18 of the elongated sheet 14 may be folded into parallel relation to the upper half or back rest portion 16 with the open frame and supporting strut inside to form a bag structure, the longitudinal marginal edges of the elongated sheet being provided with securing means to close the sides of the bag.

In the prior back rest structures of which I am aware, the supporting frame of the back rest is exposed so that when placed in the hot sun the occupant of the back rest would be liable to receive a burn should he touch the frame, particularly if the frame be made of metal. In accordance with one feature of the present invention the flexible sheet 14 is secured to the open frame in a manner such as to cover those portions thereof which may come in contact with the person using the back rest, thus assuring maximum safety and comfort of the occupant.

As best shown in Figs. 2 and 4, the open frame 10 is substantially U-shaped and the vertical legs thereof are entirely covered by loops 20 of flexible material attached to the upper portion 16 of the sheet 14, the loops being formed to permit the vertical legs to be extended therethrough. With this construction it will be seen that the sheet material may be easily and quickly attached to or detached from the frame for laundering or replacement of the sheet.

The supporting strut 12, as herein shown, may comprise a wire rod bent in the form of an X

closed at its lower end and provided with horizontally extended pin portions 22 at the free ends of the X arranged to fit into openings formed in the upper ends of the vertical legs of the U-frame to provide a pivotal connection with the frame. The pin portion 22 may and preferably will also extend through openings in the loops 20 thus serving to hold the sheet 14 in assembled relation with the frame when in use. The metal supporting strut 12 may be sufficiently rigid to retain the pin portions 22 in assembled relation with the frame 10 and the cross arms of the strut are capable of being sprung inwardly to remove the pin portions when disassembling the structure. Flexible tapes 24 connected between the lower ends of the frame 10 and strut 12 serve to limit the pivotal movement of the members and to dispose the frame at a convenient angle when in use.

When the back rest is to be used as a bag, the strut 12 is rocked inwardly parallel to the frame 10 and the lower portion 18 of the flexible sheet 12 is folded up parallel to the upper portion 16. Any usual or preferred expedient may be employed to fasten the longitudinal marginal edges of the upper and lower portion together to close the sides, and, as herein illustrated, the securing means may comprise buttons 26 attached to flap portions 28 which latter are secured to the marginal edges of the sheet adjacent the upper half 16 thereof. In operation, the flaps 28 are folded inwardly to present the buttons in a position to be received in the button holes 30 formed in the lower half of the elongated sheet. The outer ends of the sheet may be provided with handles 32 for convenience in carrying the bag, and, a pocket 34 may be sewn in the sheet if desired. The bag in its closed position is illustrated in Figs. 5 and 6.

Referring now to Figs. 3 and 7, a modified form of the combination back rest and bag structure includes a second U-shaped open frame 36 for the lower half 18 of the elongated sheet and which is arranged to be extended through loop members 38 similar to the loops 20 above described. The U-frame members 10, 36 may be connected at their horizontal arms by endless strap members 40 or by any other preferred means to permit the U-frames to be folded together in parallel relation, as shown in Fig. 7, to form side closures for the bag. In order to retain the U-frames in their closed position a ring 42 is provided on the upper end of each vertical leg of the frame 10 which rings are arranged to loop over the free ends 44 of the U-frame 36, as illustrated.

From the above description it will be seen that the present invention provides a superior combination back rest and bag structure in which none of the frame portions are exposed in a position to cause discomfort to the occupant when in use and in which the flexible sheet material is detachably secured to the frame in a manner such as to permit removal thereof for laundering or other purposes.

While the preferred embodiment of the invention has been herein illustrated and described, it will be understood that the invention may be embodied in other forms within the scope of the following claims.

Having thus described the invention what is claimed is:

1. In a combination back rest and bag structure, an elongated flexible sheet provided upon one surface and adjacent the marginal side edges of the upper half of the sheet with elongated and parallel loops, a U-shaped framework having the legs of the U inserted through the open loops and with the cross member of the U disposed below the ends of the loops and extending across the mid-section of the elongated sheet, a supporting strut having the upper ends thereof free to be capable of being compressed toward one another to permit the ends when released to be extended laterally through openings formed in the upper end portions of the aforesaid loops and through the legs of said U-shaped frame member whereby to detachably secure the elongated sheet to the supporting frame member and to pivotally attach the strut to the frame member and to the said flexible sheet, the lower half of said flexible sheet being of sufficient length to permit it to be folded upwardly to enclose therein the U-shaped frame and said strut and into a position in which the top and bottom edges of said elongated flexible sheet are in substantial alignment, and means for detachably securing together the thus folded half sections of the flexible sheet in bag forming relation.

2. In a combination back rest and bag structure, an elongated flexible sheet provided upon one surface and adjacent the marginal side edges of the upper half of the sheet, with elongated and parallel loops, a U-shaped framework having the legs of the U inserted through the open loops and with the cross member of the U disposed below the ends of the loops and extending across the mid-section of the elongated sheet, a supporting strut having the upper ends thereof extended through openings formed in the upper end portions of the aforesaid loops and through the legs of said U-shaped frame member whereby to detachably secure the elongated sheet to the supporting frame member and to pivotally attach the strut to the frame member and said flexible sheet, the lateral portions of said upper half section of said elongated flexible sheet being provided with flaps extended beyond the side edges thereof and adapted to cooperate with the lower half section of said sheet when the latter has been folded into bag-forming position to form with said folded sections a bag, said flaps and said lower half section being provided with means for detachably securing the parts together.
